UNITED STATES PATENT OFFICE.

ERIC NELSON, OF WILMINGTON, CALIFORNIA, ASSIGNOR, BY MESNE ASSIGNMENTS, TO
PACIFIC DOOR AND SASH COMPANY, A CORPORATION OF CALIFORNIA.

WALL SEAT.

Application filed May 10, 1924. Serial No. 712,274.

My invention relates to wall seats which may be shifted out of the way when not in use, and the objects of my invention are: first, to provide a wall seat which, when the same is folded up or shifted inwardly, forms a part of the outer portion of the wall on which it is supported; second, to provide a wall seat structure in which the back member forms a part of the wall when the seat member is shifted downwardly to a usable or an operative position; third, to provide a seat structure of this class in combination with a wall having a recess therein, in which the back member of the seat structure is loosely positioned within the recess of the wall and is shifted inwardly and outwardly by the movement of the seat member; fourth, to provide a seat structure of this class in which certain casing members surrounding the recess in the wall form a stop means for the back member, which back member is adapted to be forced outwardly against said casing members by means of an upwardly extending member at the rear portion of the seat member; fifth, to provide a wall seat structure of this class which has no levers, springs, or other operative members which are likely to get out of order; sixth, to provide a novelly constructed wall seat, and seventh, to provide a wall seat which is very simple and economical of construction, durable, easy to install, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a side elevational view of my wall seat in connection with a wall structure, showing the casing in the wall structure, and other members, in section, with the section taken through 1-1 of Fig. 3, and showing by dotted lines certain shifted positions of the seat and back members; Fig. 2 is a side elevational view of my wall

seat folded up and positioned in a recess of a wall structure, showing the casing, forming said recess, and other members, in section to facilitate the illustration, with the section taken through 2-2 of Fig. 4; Fig. 3 is a partial sectional and partial plan view thereof, with the seat in an operative position and with the section taken through 3-3 of Fig. 1, and Fig. 4 is a view similar to that of Fig. 3, with the seat folded up and with the section taken through 4-4 of Fig. 2.

Like characters of reference refer to similar parts and portions throughout the several views of the drawings.

The seat member 1, back member 2, casing 3, casing members 4, stop member 5, and the back positioning member 6, constitute the principal parts and portions of my wall seat structure.

The seat member 1, when folded up, and the back member 2 are positioned within the recess formed by the casing 3 built in the wall structure and by the frame or casing members 4 positioned at and surrounding the outer face of the casing 3. The main seat portion of the seat member 1 conforms substantially in size and shape with the opening between the casing members 4 and fills or closes said opening when the seat member is folded up. The seat member 1 is provided with a reduced portion 1^a at its end extending into the recess of said casing, which portion is somewhat thinner than the main portion of the seat member. The offset portion formed by the reduced portion 1^a and the main portion of the seat member provides a recess which is adapted to receive the lower horizontal casing member 4, the outer face of said casing member and the normally bottom surface of the seat member being substantially flush with each other when the seat member is in a raised or folded position, as shown best in Figs. 2 and 4.

The side casing members 4 extend inwardly beyond the inner sides of the upright members of the casing 3, forming a substantially continuous stop means from top to bottom at the opening of the recess. The back member 2 is provided with offset portions 2^a at each side which are adapted

to engage the inwardly extending portions of the side casing members 4 when the back member is shifted outwardly as when the seat member is in a downward or operative position. On the upper side of the portion of the seat member, positioned at all times within the recess of the casing 3, is provided an upwardly extending back positioning member 6, the normally front side 6^a thereof 10 engaging the back side of the back member when the seat member is shifted downwardly. Said side 6^a also serves as a rest for the back member when the seat is folded up. The back surface of the member 6 is 15 preferably inclined or curved in order to reduce the depth of the recess in the wall to a minimum. At the back side of the recess of the casing 3 is provided a stop member 5, against the front side of which the back member 2 is adapted to be positioned when the seat is folded up, and against the lower sides of which the inner end of the seat member 1 is adapted to bear when the same is in a downward or operative position. The 20 stop member 5 is provided with a vertical slot or cutaway portion 5^a, which provides clearance for the member 6 when the seat member 1 is rotated about its pivotal mounting at the upper edge of the lower casing member 4, which casing member supports the seat member intermediate its front and back edges at all times.

The lower edge of the back member 2 is preferably rounded at its front and back portions so that the same may slide easily on the rear portion of the seat member and the back positioning member 6, when shifting said seat member from one position to the other.

It will be here noted that the weight of the seat member holds the same in an operative position when shifted downwardly; and its weight, as well as the weight of the back member 2, holds said members in a folded position within the recess when the same are shifted to said position.

It will be noted that by cutting the offset portion at the sides of the back member at an angle, or by providing additional offset, 50 angular stop portions at the side edges thereof, the same may be inclined slightly with the vertical when the seat member is shifted outwardly.

It is obvious from this construction, as 55 illustrated in the drawings and disclosed in the foregoing specification, that there is provided a wall seat structure as aimed at and set forth in the objects of the invention, and that there is provided a simple, economical and practical structure which may be embodied in a disappearing shelf, table or other supporting construction in connection with a wall; and though I have shown and described a particular construction, combination and arrangement of parts and portions,

I do not wish to be limited to this particular construction, combination and arrangement, but desire to include in the scope of my invention the construction, combination and arrangement substantially as set forth in the 70 appended claims.

Having thus described my invention, what I claim as new and desire to secure by Letters Patent, is:

1. In a seat structure, the combination 75 with a casing having a recess therein and abutment means at the sides of the recess, of a supporting member loosely mounted at its one end in said recess and provided at the portion extending into said recess with a 80 supporting means, and a recess closing member loosely mounted in said recess adapted to be positioned against the abutment means therein and flush with the front side of and closing said recess when said supporting member is shifted outwardly, said recess closing member being held in engagement with said abutment means by the supporting means of said supporting member.

2. In a seat structure, the combination 85 with a casing having a recess therein and abutment means at the sides of the recess, of a supporting member loosely mounted at its one end in said recess and provided at the portion extending into said recess with a 90 supporting means, a recess closing member loosely mounted in said recess adapted to be positioned against the abutment means therein when said supporting member is shifted outwardly, said recess closing member being 100 held in engagement with said abutment means by the supporting means of said supporting member, and a stop means secured against the back of said recess adapted to be engaged by the rear portion of said supporting member when the same is shifted downwardly.

3. In a seat means, the combination with 105 a casing having a recess therein and frame members surrounding said recess at the outer portion thereof, certain of said frame members extending inwardly beyond the sides of said recess, of a supporting member supported intermediate its ends on the lower frame member and provided at the portion 110 extending into said recess with a supporting means, and a back member loosely mounted in said recess adapted to be positioned against the inwardly extending portions of certain of said frame members and flush with the front side of and closing said recess and held in said position by the supporting means of said supporting member.

4. In a wall seat structure, the combination 125 with a wall having a recess therein and a frame surrounding said recess at the outer face of said wall, the vertical members of said frame extending inwardly beyond the sides of said recess, of a seat member freely, 130 loosely and pivotally mounted intermediate

its front and rear edges on the lower member of said frame, a back member loosely mounted within said recess adapted to engage the back sides of the inwardly extending portions of said vertical frame members when said seat member is shifted outwardly and close said recess flush with its front side, and

a stop means in said recess adapted to be engaged by the rear portion of said seat member when the same is shifted outwardly. 10

In testimony whereof, I have hereunto set my hand at Long Beach, California, this 29th day of April, 1924.

ERIC NELSON.
